UNITED STATES PATENT OFFICE

167,963

CASTER CUP OR SIMILAR ARTICLE

Betty Auer, Chicago, Ill.

Application September 29, 1950, Serial No. 12,398

Term of patent 14 years

(Cl. D10—6)

To all whom it may concern:

Be it known that I, Betty Auer, a citizen of the United States, residing at Chicago, in the county of Cook and State of Illinois, have invented a new, original, and ornamental Design for a Caster Cup or Similar Article, of which the following is a specification, reference being had to the accompanying drawings, forming a part thereof.

Fig. 1 is a top plan view of a caster cup or similar article showing my new design; and

Fig. 2 is an elevational edge view of the caster cup; and

Fig. 3 is a cross-sectional view thereof.

The dominant feature of the design resides in the portions shown in the drawings in full lines.

I claim:

The ornamental design for a caster cup or similar article, as shown and described.

BETTY AUER.
